(57) **CLAIM**

The ornamental design for a aluminum awning with cloth valance, as shown and described.

DESCRIPTION

FIG. 1 is a front perspective view of an aluminum awning with a cloth valance showing my new design with an associated permanent building structure illustrated in broken lines for environment only and forms no part of the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
